UNITED STATES PATENT OFFICE.

SAMUEL J. ANDERSON AND JOSEPH TOITRAS, OF PROVIDENCE, RHODE ISLAND.

DESIGN FOR A PEDAL-ARM FOR BICYCLES.

SPECIFICATION forming part of Design No. 27,778, dated October 26, 1897.

Application filed June 22, 1897. Serial No. 641,838. Term of patent 7 years.

To all whom it may concern:

Be it known that we, SAMUEL J. ANDERSON and JOSEPH TOITRAS, of Providence, in the county of Providence and State of Rhode Island, have invented and produced a new and original Design for Pedal-Arms for Bicycles, of which the following is a specification, reference being had to the accompanying drawing, forming part thereof.

10 The drawing is a perspective view of a pedal-arm, showing my design.

The leading feature of my design consists in the S-shaped form of the pedal-arm.

In the drawing, A indicates the pedal-arm.

15 The pedal-arm A extends from the point of connection with the driving-shaft in the semi-circular curves B B to the point C, from which the arm extends to the point D in reverse curves of less curvature, and then in a semi-circular curve to the point of connection with the pedal-shaft. A circular end is formed at the point of connection with the pedal, and the semicircular curves extend beyond the

point of connection with the driving-shaft to form a rounded end.

25 The pedal-arm is widest at the end connected with the driving-shaft, gradually diminishing in width to near the pedal, where it is somewhat enlarged to form the rounded end E.

30 The pedal-arm presents to the eye the appearance of the letter S, and when in motion the curved shape of the arm produces a novel and agreeable effect on the observer.

Having thus described our invention, what 35 we claim as new, and desire to secure by Letters Patent, is—

The design for a pedal-arm for bicycles herein shown and described.

In witness whereof we have hereunto set 40 our hands.

SAMUEL J. ANDERSON.
JOSEPH TOITRAS.
